CLAIM

The ornamental design for a shoe, as shown and described.

DESCRIPTION

FIG. 1 is a side view of a shoe showing our new design; FIG. 2 is a front perspective view thereof; FIG. 3 is an opposite side front perspective view thereof; and, FIG. 4 is a opposite side view thereof.

The even-length broken lines within the shaded area represent stitching and form no part of the claimed design. The uneven-length broken lines immediately adjacent to the shaded area define the bounds of the claimed design and form no part thereof. The uneven-length broken line showing of the six circular elements represent lacing elements that form no part of the claimed design. The uneven-length broken lines depicting the remainder of the shoe form no part of the claimed design.

1 Claim, 4 Drawing Sheets
